MOUNTING MEANS FOR SPECTACLES

David Slotsky, Cleveland, Ohio

Application May 31, 1941, Serial No. 395,903

8 Claims. (Cl. 88—47)

My invention relates to the fastening of a mounting of a spectacle to the lens of the spectacle. My mounting is for use in fastening the nose or bridge piece to the lens, for use in fastening the temple or ear piece to the lens, and for fastening any other type of mounting to the lens, in all cases where the mounting is to be secured, fastened or engaged in conjunction with a fastening hole provided in the edge of the lens.

An object of my invention is to provide a secure and adequate mounting for a lens which will not become loose. To those acquainted with the art, it is also well known that when the mounting becomes even slightly loose, the play between the lens and the mounting tends to induce a fracture of the lens.

The nature of my mounting is such that it cannot become loose after it is once permanently connected.

Another object of my invention is to provide a simple and efficient means for the fastening of my mounting to the lens. My mounting is easily installed and requires little skill in assembling the parts.

Another object of my invention is the provision of a mounting for a lens which accommodates lenses of different thicknesses.

Another object of my invention is the provision of completely filling the fastening hole on the edge of the lens so that there is no opportunity for the mounting to become loose and develop play with respect to the lens.

Another object of my invention is the provision of an arm connected to a strap member for embracing the side edge of the lens in which the arm is substantially invisible.

Another object of my invention is the provision of compressing a soft pliable sleeve into the fastening hole of the lens in order to completely fill the fastening hole and thereby prevent any play or loose movement between the mounting and the lens.

Other objects and a fuller understanding of my invention may be had by referring to the following description and claims, taken in conjunction with the accompanying drawing, in which:

Figure 1 represents a lens of a spectacle to which my mountings have been applied, both to the nose piece and the ear piece;

Figure 2 is a view of a lens of a spectacle to which my mounting has been applied to the nose piece only;

Figure 3 is a view of a lens of a spectacle to which my mounting having an invisible arm for

embracing the side edges of the lens has been applied to both the nose piece and the ear piece;

Figure 4 is an enlarged and fragmentary view of a lens illustrating the first step of mounting a soft metal sleeve in the fastening hole of the lens;

Figure 5 illustrates a view similar to Figure 4 but with the soft metal sleeve cut back to a length substantially equal to the thickness of the lens;

Figure 6 represents a side elevational view of a fragmentary portion of a strap having a round shoulder and a screw secured therein;

Figure 7 is a view illustrating the arrangement of the parts when the mounting of Figure 6 is inserted in the fastening hole of the lens of Figure 5;

Figure 8 is a cross-sectional view of my finished mounting;

Figure 9 is a view similar to Figure 8 but shows the screws being mounted in the reverse direction to that shown in Figure 8;

Figure 10 is a perspective view of my mounting having laterally extending arms from the strap portion which when mounted upon the lens appear substantially invisible; and

Figure 11 shows a front view of the mounting in Figure 10 secured to the edge of a lens.

With reference to the drawing, my mounting is indicated generally by the reference character 11 and may be employed for both the nose piece and

the ear piece as shown in Figure 1 or for the nose piece only as shown in Figure 2. In Figure 1, I show a brace or a tie bar 12, interconnecting the nose piece and the ear piece, but it is to be understood that my mounting may be employed without the use of the brace or tie bar 12. The lens of the spectacle is indicated by the reference character 10 and each is provided with a small fastening hole 18 in the marginal end thereof. Thus,

my mounting is adaptable for all cases where the mounting is to be secured, fastened, or engaged to the lens in conjunction with the hole provided therein.

My mounting comprises a strap member 13 having a round shoulder portion 14 secured thereto which is adapted to fit closely in the fastening hole 18 for a distance less than the width of the lens. As illustrated, the round shoulder portion 14 is provided with a female threaded opening to receive a screw 15 having a threaded portion 16 and a head 17. The strap member 13 is countersunk so that the head 17 of the screw fits almost flush with the outside surface of the strap member 13.

The threaded portion 16 of the screw extends beyond the shoulder portion 14 and is arranged to

project through the fastening hole 18 of the lens. The combination of the shoulder portion 14 and the threaded portion 16 of the screw 15 may be referred to as a post construction.

Mounted in the fastening hole 18 and positioned around the threaded portion 16 of the screw 15 is a soft pliable sleeve 21 capable of flowing under compression. In practice I find that a sleeve made of lead proves very satisfactory. For good results, the pliable sleeve 21 should be of such character as to flow or readily change its form under compression as distinguished from a metal sleeve which is hard or brittle. In production the soft metal sleeves 21 are made as long as the width of the thickest lens. As shown in Figure 4, the soft metal sleeve 21 is mounted in the fastening hole 18 of the lens and then the portion which extends beyond the upper surface of the lens is cut back flush with the lens as shown in Figure 5. The next step is to take the mounting in Figure 6 and insert it into the fastening hole 18 of the lens as shown in Figure 5 which when finally inserted the parts take the position as shown in Figure 7. The lower end of the soft metal sleeve 21 in Figure 7 abuts against the shoulder portion 14 and the other end of the soft metal sleeve 21 extends above the surface of the lens. The final step in securing my mounting to the lens is to threadably turn a nut 22 upon the upper end of the threaded portion 16. As the nut 22 is turned down, it abuts against the upper end of the soft metal sleeve and compresses same thereunder against the lens and against the shoulder portion in the fastening hole around the threaded portion 16 to make a good firm connection between the post construction and the lens. The soft metal sleeve as it is compressed flows into all parts of the fastening hole 18 and completely fills the same to make a good firm connection without any play. The upper end of the soft metal sleeve as the nut 22 is being turned down flares outwardly under the nut 22 and flows over the outside surface of the lens around the marginal edge of the fastening hole 18, see Figure 8. Also, some of the soft metal of the sleeve flows down between the round shoulder portion 14 and the inside edge of the fastening hole 18 to fill all possible clearances between the shoulder portion 14 and the inside surface of the fastening hole 18. The soft metal of the sleeve 21 also flows completely around the threads of the threaded portion 16. The ultimate result is that a good firm connection is made between the post construction and the lens so that there is no opportunity for any play to initially start between the post construction and the fastening hole 18 of the lens. In addition, there is no tendency for the nut 22 to become loose as it is firmly embedded in the soft metal sleeve and thus the tendency to become loose is not present.

In Figure 9 I illustrate how the screw 15 and the nut 22 may be mounted in the reverse order from that shown in Figure 8. In Figure 9 the soft metal sleeve 21 is firmly compressed into the fastening hole of the lens by the head 17 of the screw and the nut 22 is threadably engaged to the threaded portion 16 of the screw and abuts against the outside surface of the strap member 13. In Figures 8 and 9, after the nut 22 is tightly turned down upon the threaded portion 16, the exposed end of the threaded portion 16 is cut back and made smooth and flush with the top surface of the nut 22.

In Figures 3, 10 and 11 I show an added pro-

5 vision mounted on my strap member 13 which comprises a laterally extending arm 23 for embracing the side edges of the lens to keep the mounting from turning with respect to the lens. The laterally extending arm 23 extends away from the strap member 13 on both sides thereof and forms two narrow lateral portions 24. The outside edge of the narrow lateral portion 24 is indicated by the reference character 25 and in my invention the outside edge 25 is substantially in alignment with the outside edge 26 of the lens, see Figures 3 and 11. On the end of each narrow lateral portion 24 is provided a tab 27 which extends upwardly and engages the outside edge of the lens 26 at spaced distances from the strap member 13. The narrow lateral portions 24 are relatively thin and lie on the rear side of the lens near the edge thereof. Under actual observation, the narrow lateral portions 24 appear substantially invisible. The invisible nature of the narrow lateral portions 24 appears to result from the fact that they lie in rear of the lens and near the outside edge thereof which positions them in a region coming under the reflection of the side edge portions of the lens so that an observer cannot see the marginal lateral portions 24 so well as they could be seen if they were located a substantial distance away from the outside edge of the lens. The tabs 27 are relatively small and harmonize with the invisible character of the marginal lateral portions 24 of the arm 23. That is to say, the construction of my arm arrangement 23 takes advantage of the reflection resulting from the side edge surfaces of the lens in the region of the mounting.

40 Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

45 I claim as my invention:

1. A mounting for a lens having a fastening hole near the edge thereof comprising, in combination, strap means for engaging one side of the lens, post means secured to the strap means and arranged to extend through the fastening hole of the lens, said post means having a round shoulder portion adjacent the strap means and a male threaded portion of less diameter than the shoulder portion extending therebeyond, said shoulder portion fitting closely in the fastening hole and extending thereinto for a distance less than the width of the lens with the male threaded portion continuing on through the fastening hole, a soft metal sleeve capable of flowing under compression positioned around the male threaded portion and fitting into the fastening hole with one of its ends abutting against the shoulder portion, and female threaded means engaging the male threaded portion for holding the lens on the post means and against the strap means, said female threaded means abutting against the other end of the soft metal sleeve and compressing same thereunder against the lens and against the shoulder portion in the fastening hole around the male threaded portion to make a good firm connection between the post means and the lens, said other end of the soft metal sleeve being flared outwardly around the marginal edge of the fastening hole and under the female threaded means.
2. A mounting for a lens having a fastening hole near the edge thereof comprising, in combination, strap means for engaging one side of the lens, post means secured to the strap means and arranged to extend through the fastening hole of the lens, said post means having a round shoulder portion adjacent the strap means and a male threaded portion of less diameter than the shoulder portion extending therebeyond, said shoulder portion fitting closely in the fastening hole and extending thereinto for a distance less than the width of the lens with the male threaded portion continuing on through the fastening hole, a soft metal sleeve capable of flowing under compression positioned around the male threaded portion and fitting into the fastening hole with one of its ends abutting against the shoulder portion, and female threaded means engaging the male threaded portion for holding the lens on the post means and against the strap means, said female threaded means abutting against the other end of the soft metal sleeve and compressing same thereunder against the lens and against the shoulder portion in the fastening hole around the male threaded portion to make a good firm connection between the post means and the lens, said other end of the soft metal sleeve being flared outwardly around the marginal edge of the fastening hole and under the female threaded means.

2. A mounting for a lens having a fastening hole near the edge thereof comprising, in combination, strap means for engaging one side of the lens, post means secured to the strap means and arranged to extend through the fastening hole of the lens, said post means having a shoulder portion adjacent the strap means and a male threaded portion extending therebeyond, said shoulder portion fitting closely in the fastening hole and extending therewith for a distance less than the width of the lens with the male threaded portion continuing on through the fastening hole, a soft pliable sleeve capable of flowing under compression positioned around the male threaded portion and fitting into the fastening hole with one of its ends abutting against the shoulder portion, and female threaded means engaging the male threaded portion for holding the lens on the post means and against the strap means, said female threaded means abutting against the other end of the soft pliable sleeve and compressing same thereunder against the lens and against the shoulder portion in the fastening hole around the male threaded portion to make a good firm connection between the post means and the lens, said other end of the soft pliable sleeve being flared outwardly around the marginal edge of the fastening hole and under the female threaded means.

3. A mounting for a lens having a fastening hole near the edge thereof comprising, in combination, strap means for engaging one side of the lens, post means secured to the strap means and arranged to extend through the fastening hole of the lens, said post means having a shoulder portion adjacent the strap means and a male threaded portion extending therebeyond, said shoulder portion fitting closely in the fastening hole and extending therewith for a distance less than the width of the lens with the male threaded portion continuing on through the fastening hole, a soft metal sleeve capable of flowing under compression positioned around the male threaded portion and fitting into the fastening hole with one of its ends abutting against the shoulder portion, and female threaded means engaging the male threaded portion for holding the lens on the post means and against the strap means, said female threaded means abutting against the other end of the soft metal sleeve and compressing same thereunder against the lens and against the shoulder portion in the fastening hole around the male threaded portion to make a good firm connection between the post means and the lens, arm means connected to the strap means for engaging the edge of the lens, said arm means having a narrow lateral portion extending from each side of the strap means along the edge of the lens on the rear side thereof, the outside edge of the narrow lateral portions and the edge of the lens being substantially in alignment, the ends of the narrow lateral portions each having a tab for engaging the edge of the lens at spaced points from the strap means.

4. A mounting for a lens having a fastening hole near the edge thereof comprising, in combination, strap means for engaging one side of the lens, post means secured to the strap means and arranged to extend through the fastening hole of the lens, said post means having a shoulder portion adjacent the strap means and a male threaded portion extending therebeyond, said shoulder portion fitting closely in the fastening hole and extending therewith for a distance less than the width of the lens with the male threaded portion continuing on through the fastening hole, a soft metal sleeve capable of flowing under compression positioned around the male threaded portion and fitting into the fastening hole with one of its ends abutting against the shoulder portion, and female threaded means engaging the male threaded portion for holding the lens on the post means and against the strap means, said female threaded means abutting against the other end of the soft metal sleeve and compressing same thereunder against the lens and against the shoulder portion in the fastening hole around the male threaded portion to make a good firm connection between the post means and the lens, said other end of the soft metal sleeve being flared outwardly around the marginal edge of the fastening hole and under the female threaded means.

5. A mounting for a lens having a fastening hole near the edge thereof comprising, in combination, strap means for engaging one side of the lens, post means secured to the strap means and arranged to extend through the fastening hole of the lens, said post means having a shoulder portion adjacent the strap means and a male threaded portion continuing on through the fastening hole, a soft metal sleeve capable of flowing under compression positioned around the male threaded portion and fitting into the fastening hole with one of its ends abutting against the shoulder portion, and female threaded means engaging the male threaded portion for holding the lens on the post means and against the strap means, said female threaded means abutting against the other end of the soft metal sleeve and compressing same thereunder against the lens and against the shoulder portion in the fastening hole around the male threaded portion to make a good firm connection between the post means and the lens, arm means connected to the strap means for engaging the edge of the lens, said arm means having a narrow lateral portion extending from each side of the strap means along the edge of the lens on the rear side thereof, the ends of the narrow lateral portions each having a tab for engaging the edge of the lens at spaced points from the strap means.

6. A mounting for a lens having a fastening hole near the edge thereof comprising, in combination, strap means for engaging one side of the lens, a shoulder portion secured to the strap means and arranged to extend in the fastening hole for a distance less than the width of the lens, a soft metal sleeve capable of flowing under compression adapted to fit into the fastening hole with one of its ends abutting against the shoulder portion, and securing means having an extension portion extending through the sleeve and engaging the shoulder portion for holding the lens on the shoulder portion and against the strap means, said securing means having an enlarged end portion abutting against the other end of the soft metal sleeve and compressing same thereunder against the lens and against the shoulder portion in the fastening hole around the extension portion to make a good firm connection between the strap means and the lens, said other end of the soft metal sleeve being flared outwardly around the marginal edge of the fastening hole and under the said enlarged end portion.

7. A mounting for a lens having a fastening hole near the edge thereof comprising, in combination, strap means for engaging one side of the lens, a shoulder portion secured to the strap means and arranged to extend in the fastening hole for a distance less than the width of the lens, a soft metal sleeve capable of flowing under compression adapted to fit into the fastening hole with one of its ends abutting against the shoulder portion, and securing means having an extension portion extending through the sleeve and engaging the shoulder portion for holding the lens on the shoulder portion and against the strap means, said securing means having an enlarged end portion abutting against the other end of the soft metal sleeve and compressing same thereunder against the lens and against the shoulder portion in the fastening hole around the extension portion to make a good firm connection between the strap means and the lens, said other end of the soft metal sleeve being flared outwardly around the marginal edge of the fastening hole and under the said enlarged end portion.

7. A mounting for a lens having a fastening hole near the edge thereof comprising, in combination, strap means for engaging one side of the lens, a shoulder portion secured to the strap means and arranged to extend in the fastening hole for a distance less than the width of the lens, a soft metal sleeve capable of flowing under compression adapted to fit into the fastening hole with one of its ends abutting against the shoulder portion, and a screw having a threadable extension portion extending through the sleeve and threadably engaging the shoulder portion for holding the lens on the shoulder portion and against the strap means, said screw having a head portion abutting against the other end of the soft metal sleeve and compressing same thereunder against the lens and against the shoulder portion in the fastening hole around the threadable extension portion to make a good firm connection between the strap means and the lens, said other end of the soft metal sleeve being flared outwardly around the marginal edge of the fastening hole and under the said head portion.

8. A mounting for a lens having a fastening

hole near the edge thereof comprising, in combination, strap means for engaging one side of the lens, a shoulder portion secured to the strap means and arranged to extend in the fastening hole for a distance less than the width of the lens, a sleeve constructed of pliable material adapted to fit into the fastening hole with one of its ends abutting against the shoulder portion, and securing means having an extension portion extending through the sleeve and engaging the shoulder portion for holding the lens on the shoulder portion and against the strap means, said securing means having an enlarged end portion abutting against the other end of the pliable sleeve and compressing same thereunder against the lens and against the shoulder portion in the fastening hole around the extension portion to make a good firm connection between the strap means and the lens, said other end of the soft pliable sleeve being flared outwardly around the marginal edge of the fastening hole and under the said enlarged end portion.

DAVID SLOTSKY.
